UNITED STATES PATENT OFFICE.

ANGELO PAPOULIAS, OF STEUBENVILLE, OHIO.

CHANGE-MAKING DEVICE.

Application filed May 31, 1923. Serial No. 642,691.

To all whom it may concern:

Be it known that I, ANGELO PAPOULIAS, a citizen of the United States, and resident of Steubenville, in the county of Jefferson and State of Ohio; have invented certain new and useful Improvement in Change-Making Devices, of which the following is a specification.

This invention relates to an improvement 10 in change making devices of the type forming the subject-matter of my co-pending application, filed Jan. 17, 1922, Serial No. 529,891.

The object of this invention is to provide 15 a change making device of this character and having all of the advantages of the one disclosed in the copending application hereinabove referred to and wherein the mechanism for carrying out the functions and 20 achieving the purposes is simpler, more durable and susceptible of more economical manufacture and upkeep, the parts of the present invention requiring little or no attention during the life of the machine and 25 at the same time being extremely easy and smooth in operation.

Another object is to provide a device of 30 this character having detachably organized therewith a register actuated by the amount purchased keys of the machine and preserving a record of the total of the amounts purchased.

A further object is to provide locking 35 mechanism for the means which serve to actuate the ejector for the coins until an amount purchased key has been operated.

A still further object is to improve and 40 enhance the action and efficiency of the ejecting mechanism and the means for selectively rendering the sliding plungers active or inactive with respect thereto.

Other objects and advantages of the invention reside in certain novel features of 45 the construction, combination and arrangement of parts which will be hereinafter more fully described and particularly pointed out in the appended claims, reference being had to the accompanying drawings forming part of this specification, and 50 in which:

Figure 1 is a plan view of the preferred embodiment of the invention;

Figure 2 is a view thereof in front elevation;

Figure 3 is a vertical sectional view, 55 taken on line 3—3 of Figure 1;

Figure 4 is a similar view on line 4—4 of Figure 1;

Figure 5 is a view in horizontal section, 60 taken on line 5—5 of Figure 4;

Figure 6 is a fragmentary view in vertical section, showing the motion transmission means between the amount purchased key and a connecting plate;

Figure 7 is a view in transverse section 65 on line 7—7 of Figure 4, illustrating the ejectors;

Figure 8 is a group view in perspective showing details of the ejector;

Figure 9 is a detail view, partly in section and partly in elevation, illustrating the 70 construction of the register;

Figure 10 is a perspective view, showing 75 the manner in which the disks of the register are marked;

Figure 11 is a view in section on line 11—11 of Figure 9, showing one form of transfer mechanism which may be employed between the disk of the register representing five cent values and the next disk of 80 higher order; and

Figure 12 is a detail view in fragmentary perspective.

Referring to the drawings wherein for 85 the sake of illustration is shown the preferred embodiment of the invention, the numeral 1 designates the housing of the change making device. It is to be understood that this housing may be of any desirable and suitable design or type and that 90

the showing in the drawings is merely for the sake of illustration. At the forward end of the housing a coin magazine, designated generally at 2 is provided and within the coin magazine stacks of coins 3 are arranged and are supported at their lower ends by any suitable type of support, one such support being shown for the sake of illustration as comprising an angle bar 4 having its vertical flange bolted or otherwise suitably secured to the structure of the housing and having its horizontal flange disposed to support the stacks of coins and if found desirable suitably cut away below each stack, as shown in Figure 5. Below the coin stacks a delivery chute 5 is arranged so that the coins which are ejected from the stacks are fed down to the 95 100 105

readily accessible trough of the delivery chute. These elements in themselves form no part of the present invention and of course may be of any type or construction and are referred to and shown generally merely for the sake of illustration.

At this point it is to be understood that the novel features of the present invention are provided in units so as to be adapted to effect the changing of coins of various denominations. This is illustrated to advantage in the arrangement shown in Figures 1 and 2, wherein four such units designated at 6, 7, 8 and 9 are provided. These units differ from each other only in that the novel structural features which characterize the present invention are duplicated or provided in progressively increasing number in the units 6, 7, 8 and 9 in order to adapt the machine for making change for coins of the value of \$1.00; \$.50; \$.25 and \$.10. Obviously the novel structural features may be duplicated to any desired degree.

In view of the foregoing it will be understood that it will be sufficient to describe one of these units such for instance as the unit provided for changing coins of the value of \$.25, and this description will apply to the other units of the invention except that the structural features thus described are duplicated in different degrees or provided in different numbers in the other units.

In the unit 7 as well as in the other units, an ejector, designated generally at 10 is provided for each coin stack and each ejector is housed and operated in an individual cell or opening 10^a provided therefor in the structure of the housing. Each ejector comprises a sliding ejector plate 11 mounted for horizontal sliding movement in guide grooves 12 provided in the opposite walls of its cells. The forward end of each ejector plate 11 is provided with a curved notch 13 which conforms to the portion of the periphery of the lowermost coin of the stack with which it is engaged. Adjacent its rear end the ejector plate is provided with a transverse slot 14 which extends entirely through the plate but only part of the way across the same. A coil spring 15 is arranged in the opening 11 and engages the front wall of said opening at one end and the bars of an open rectangular frame 16 at its other end, the frame 16 being secured to the ejector plate 12 and sliding therewith so that the coil spring 15 is effective to resiliently hold the ejector plate retracted and against movement tending to eject coins from the stack with which the ejector is associated.

A plurality of sliding plungers 17 is provided, there being one such plunger for each ejector, and in the embodiment shown there are three such plungers and three stacks of coins, two stacks of 10¢ coins and one stack of 5¢ coins. As shown in the drawings each

plunger 17 is mounted for horizontal reciprocatory movement on a plurality of peripherally grooved rollers 18 suitably journaled on shafts 19 carried by the housing, the plungers 17 being prevented from being vertically displaced by smooth retaining bars 20 carried by the housing and arranged immediately above the plungers.

Means is provided for selectively rendering the plungers active or inactive with respect to the ejectors with which they are associated so that when the plungers are actuated they are effective to operate the ejectors or not under the control of the means now to be described. This means includes a vertically reciprocable connecting plate 21 for each ejector, each such plate 21 being mounted for vertical sliding movement in the slot 14 of the sliding plate 11 of the ejector with which it is associated and being disposed to slidably engage one side of the open frame 16, connected to such sliding plate 11. When the plate 21 is lowered as far as it may be in the slot 14 it lies in the path of the plunger associated with the ejector so that when the plunger is actuated and moves forwardly its motion will be transmitted to the sliding plate 11 of the ejector. On the contrary when the plate 21 is raised to a point where it is almost withdrawn from the cell or opening 10^a it will lie out of the path of the plunger so that the motion of the plunger will not be transmitted to the sliding plate 11 of the ejector.

For the purpose of controlling these connecting plates 21 as well as for other purposes which will hereinafter appear, a key 22 is provided for each plate 21 and are herein described as the amount purchased keys. Each key 22 includes a stem 23 slidably mounted in a bearing 24 and if desired held in uppermost position by means of a spring 25. The lower end of the stem 23 of each key 22 is provided with a transverse laterally extending heel 26 which engages the upper edge of a lever 27 adjacent one end thereof, the opposite end of the lever being pivotally mounted on a shaft 28. One such lever 27 is provided for each key but the shaft 28 serves as a common fulcrum for all the levers. Intermediate its ends each lever 27 is connected by a link 29 with one end of a lifting lever 30 fulcrumed on a shaft 31 and having its forward end connected, as at 32, with a connecting plate 21. Thus each ejector is independently controlled from its individual key 22.

Means is provided for releasably holding the keys 22 depressed against the action of the springs 26 and for this purpose a plurality of spring pressed detents 33 are provided, there being one such detent 33 for each key 22 and all of the detents being pivotally mounted on a common supporting shaft 33^a. The hooked ends 24 of the de-

tents are engageable with lugs or teeth 35 provided on the stems 23 of the key 22 and the hooked ends 34 and lugs 35 are provided with coacting inclined surfaces 36 and 37 whereby the detents and teeth are automatically engaged when the keys are depressed. A spring pressed release key 38 is provided and its stem 39 carries at its lower end a laterally extending bar 40 which is common to all of the detents 35 and engageable therewith for the purpose of swinging the detents so as to disengage their hooked ends 34 from the teeth 35. The detents 33 have tail extensions 41 so as to be automatically disengaged in certain stages of the operation as will hereinafter more fully appear.

The plungers of each unit are actuated from a single key and in unit 7 now being described such key is designated at 45, and is herein termed the amount tendered key. Such key has its stem 46 mounted in a bearing 47 and is spring pressed, as at 48. The lower end of the stem 46 carries a laterally extending horizontal bar 49 which engages the top edges of a number of levers 50 adjacent the rear ends thereof. The forward ends of the levers 50 are pivotally mounted on a shaft 51. One such lever 50 is provided for each plunger 20 and as there are three plungers in this unit there are three levers 50. Intermediate its ends and preferably adjacent its rear end each lever 50 is connected by a link 52 with one arm of a bell crank lever 53 fulcrumed on the shaft 54. The depending arm of each bell crank lever is connected to a plunger 17 by means of a pin and slot connection 55. In this manner when a key 45 is depressed all of the levers 50 will be swung downwardly as the bar 49 carried by the stem 46 of the key 45 engages all of these levers. As these levers 50 swing downwardly the bell crank levers 53 are rotated about their fulcrum 54 since they are connected to the levers 50 by the links 52, and this movement of the bell crank levers is in turn transmitted to the plungers 17 by the pin and slot connections 55. Whether or not the movement of the plungers is transmitted to the sliding plates of the ejectors to eject the coins from the stacks with which the ejectors are associated depends on whether or not the keys 22 have been depressed as has been previously described.

Means is provided for preventing actuation of the ejectors until at least one amount purchased key has been depressed and includes a pair of rods 60, one such rod being arranged at each side of the housing and both of the rods being arranged in the same horizontal plane and parallel to the plungers 17. As shown in the drawings a number of peripherally grooved rollers 59 rotatably mounted on the same shafts 19 which carry the similar rollers 18 for the

plungers 17 support the rods 60 and the same retaining bars 20 which coact with the plungers 17 also prevent vertical displacement of the rods 60. At their rear ends these rods 60 are operatively associated by 70 pin and slot connection 61 with a bell crank lever 62 fulcrumed on the shaft 54 and connected by links 63 to the arms 64 of a U-shaped frame 65, the legs of which are pivotally mounted on the shaft 51 and the body 75 portion 66 of which is extended downwardly and engaged with the underside of the levers 50 and thus it is that any downward movement of the levers 50 must also be accompanied by a downward movement of the frame 65 and consequently by a forward movement of the side rods 60. At the forward ends of the rods 60, latches 67 are arranged; these latches being pivotally mounted on the side walls of the casing 80 or housing 1 and being engageable with pins 68 projecting laterally from the side bars 60 to prevent movement of the side rods and consequently of the plungers 17 or keys 45 and associated mechanism. It 90 is proposed to have the latches 67 under the control of the amount purchased keys 22 so that when any one or more of these keys are depressed the latches are released from their pins 68. In order to carry out 95 this operation a U-shaped frame 70 is provided and has its arms 71 pivotally mounted on the shaft 28. The body portion 72 of the frame is offset downwardly and underlies and engages the lower edges 100 of the levers 27 so that any downward movement of any one or more of the levers 27 which always occurs when a key 22 is depressed must be accompanied by a downward movement of the frame 70. The 105 arms 71 of the frame 70 are connected by links 73 with rocking levers 74 mounted on the shaft and having their opposite ends connected by links 75 with the latches 67. A retractile coil spring 76 is provided 110 for each lever 74 and has one end connected to the lever 74 and has its opposite end connected to a lug 78 and tends to return the lever to such position as to engage the latch 67 with its pin 68.

A register indicated generally at 79 is organized with the change-making device and includes a number of disks, designated at 80, 81 and 82. The disk 80 is detachably secured in any suitable manner to a solid shaft 120 83 and on the end of the shaft 83, opposite the disk 80 it is enlarged and has teeth 84 formed thereon. The disk 81 is fixed to one end of a sleeve shaft 85 having teeth 86 formed on the enlarged end thereof opposite the disk 81. This sleeve shaft is assembled on the solid shaft 83 and in turn it has assembled on a reduced portion thereof a second sleeve shaft 87 which is attached to the disk 82. The disks 80 and 81 must be 125 130

removably attached to their respective shafts in order to enable assembly of these parts as shown in Figure 9. Three sectors, designated at 90, are provided and each sector has formed thereon a tooth 91. One sector 90 has its tooth engaged with the teeth 84 and the other two have their teeth engaged with the teeth 86. Each sector is pivotally mounted, as at 92, on a lever 93 and engages a stop 94 formed on lever 93, the sector 90 being resiliently held against its stop 94 by a light retractile coil spring 95. The levers 93 are fulcrumed on the shaft 31 and are connected by links 99 with actuating levers 100 fulcrumed on a shaft 101 and connected by pin and slot connection 102 with the stem 23 of the amount purchased keys. Thus when the amount purchased keys are depressed segments are thrown into engagement or mesh with the teeth of their gears so that the amount registered is controlled or determined by the keys 22, it being understood that the five-cent key controls the five cent disk 80 of the register, the ten-cent keys 22 the ten cent disk, etc.

The depression of the keys 22 do not however actuate the register but only render the same operative or capable of operation by bringing into mesh the sectors and the teeth 30 and shafts of the registers. The sectors are actuated when the keys 45 are depressed for as these keys 45 are depressed the side rods 60 are moved forwardly as previously described and this movement of the rods is transmitted to the sectors by means of a swinging U-shaped frame 105 having arms 106 pivotally mounted on a shaft 107, the arms being connected to the side rods 60 by the pins 68 which operate in slots 108 formed in the arms 107 to provide a pin and slot connection between these parts. The body portion 109 of the frame is engageable with the sectors for swinging the same through their operative movements. 45 Retractile coil springs 110 tend to return the frames 105 to the position shown in Figure 4.

It is to be understood that the register 79 may be of any conventional construction but for the sake of illustration one form of register is shown generally. In the register shown the periphery of the disks 80 and 81 bear decimal indicia and the disk 82 unit indicia, the indicia of disks 81 and 82 preferably progressing from one to ten and that of the disk 80 being alternately five and zero. Between the disks 81 and 82 any conventional transfer mechanism (not shown) is employed for advancing the disk 82 one step each time the disk 81 makes a complete rotation and between the disks 80 and 81 suitable transfer mechanism is employed for advancing the disk 81 one step for every two or every other step that the disk 82 is advanced. For the sake of illustration this

latter transfer mechanism between the disks 80 and 81 is shown as comprising an extension collar 115 rigid or integral with the sleeve shaft 85 or disk 81 and provided with five peripheral pockets 116 each of which 70 pockets are formed with a vertical wall and an inclined or curved wall. In the assembly the collar is received in a cavity 80^a provided in the disk and in this same cavity five gravity pawls 117 operate, the pawls being 75 pivotally mounted on the adjacent lateral face of the disk 80 and coacting with the pockets 116. Stops 118 coact with the pawls and if found desirable light springs may be employed for resiliently holding the pawls 80 against the stops.

In operation it will be understood that the keys 22 corresponding to the amount purchased are first depressed and if for instance the amount of a purchase is 10¢ 85 then a single 10¢ key is depressed. Depression of the keys 22 or any one of them carries out three functions in that it first selects the plungers 20 which are to be inactive to actuate their ejectors. For instance in the example given when a single 10¢ key is depressed the connecting plate 21 associated with the ejector for one 10¢ stack is raised so that the associated plunger when actuated will slide idly through the frame 95 16 and coil spring 15 and will not move the plate 11 to eject the one coin from the 10¢ stack. The connecting plates 21 of the 5¢ stack and of the other 10¢ stack are however left in their lower position wherein 100 they are disposed to be engaged by their plungers. The second purpose accomplished by the depression of the key 22 is the unlocking of the side rods 60 for as any one of the keys 22 is depressed the frame 77 105 swings downwardly under the action of the lever 27 and the latches 67 are elevated through the links 73 and 75 and the lever 74. The third purpose accomplished is the operative engagement of the operating parts 110 of the register for the sectors are brought into engagement with the teeth of the shafts of the register as previously described. Similarly depression of the key 45 accomplishes three ends. The primary purpose 115 of the depression of this key is the actuation of the plungers 20 which engage with the connecting plate or plates 21 which remain in their lower position and in the path of the plunger to actuate the ejector with 120 which such ejector plates are associated. The second purpose accomplished by the depression of the key 45 is the actuation of the sector 90 of the operating means for the register for as the key 45 is depressed 125 the frame 65 is swung downwardly. The side rods 60 are advanced forwardly and the frame 105 is swung rearwardly and engages the sector to throw the same through one phase of its oscillation. The final end 130

accomplished by the depression of the key 45 is the automatic release of the detents 35 for as the key reaches its lowermost position the bell crank 53 is swung to such position that its vertical arm strikes against the extension 40 of the tail of the detent 35 to kick the detent out of engagement with its tooth 37 thereby releasing the keys 22 and permitting the springs 25 to return 10 them to normal position and also permitting the latches 67 to again engage the pins 68 and the connecting plates 21 to return to lowermost position.

It is to be understood that all of the parts 15 of the register 79 and its actuating and controlling mechanism are detachably mounted in assembly so that the register may be readily taken from the machine thereby making the use of the register optional.

20 I claim:

1. In a change making device, a money changing unit including a coin holder, an ejector for said holder, a sliding plunger, a slidable connecting plate between the sliding plunger and the ejector and a key for controlling said slidable connecting plate.

2. In a change making device, a money changing unit including a plurality of coin holders, ejectors for the holders, a plurality 30 of sliding plungers, key operated means controlling the plungers, shiftable connecting elements between the sliding plungers and the ejectors, keys selectively controlling the shiftable connecting elements, locking mechanism controlled by said keys for preventing operation of the plungers and the key operated means thereon until one or more of said keys have been depressed.

3. In a change making device, a money 40 changing unit including a plurality of coin holders, ejectors for the holders, a plurality of sliding plungers, key operated means controlling the plungers, shiftable connecting elements between the plungers and the ejectors, keys selectively controlling the shiftable connecting elements, a register, means controlled by said keys for setting the register and determining the action thereof, and motion transmission means between said key operated means, and said last mentioned means for actuating the register from the key operated means.

4. In a change making device, a money 55 changing unit including a plurality of coin holders, ejectors for the holders, a plurality of sliding plungers, key operated means controlling the plungers, shiftable connecting elements between the plungers and the ejectors, keys selectively controlling the shiftable 60 connecting elements, a register, means controlled by said keys for setting the register and determining the action thereof, motion transmission means between said key operated means, and said last mentioned means for actuating the register from the key op-

erated means, and locking mechanism controlled by said keys for preventing operation of the plungers and of the key operated means therefor until one or more of said keys have been depressed. 70

5. In a change making device, a money changing unit including a plurality of coin holders, ejectors for said holders including horizontal sliding ejector plates having slots therethrough, spring means for maintaining 75 said plates retracted, a plurality of sliding plungers, key operated means controlling the plungers, vertically slidable connecting plates operatively fitted in the slots of the ejector plates and adapted to be positioned 80 to be engaged by the plunger or to be disposed to lie out of the path thereof and keys for selectively controlling the position of said connecting plates.

6. In a change making device, a money 85 changing unit including a plurality of coin holders, ejectors cooperating with the holders, a plurality of sliding plungers, key operated means controlling the plungers and comprising a plurality of key controlled levers, and motion transmission means between the levers and the plungers, a frame engaging said levers and actuated therefrom, side rods, motion transmission between the frame and the side rods whereby the side rods partake of the motion of the levers, latches 90 operable with the side rods, shiftable connecting elements between the sliding plungers and the ejectors, keys selectively controlling the shiftable connecting elements, 95 and release means for said latches controlled by said keys. 100

7. In a change making device, a money changing unit including a coin holder, an ejector for said holder, a sliding plunger, a shiftable connecting element between the sliding plunger and the ejector, keys for selectively controlling said connecting elements, key operated means for actuating the sliding plungers, a register, operating means 105 for the register connectible and disconnectible therewith under the control of said keys, and means for actuating said operating means from the key operated means. 110

8. In a change making device, a money 115 changing unit including a coin holder, an ejector for said holder, a sliding plunger, a shiftable connecting element between the sliding plunger and the ejector, keys for selectively controlling said connecting elements, key operated means for actuating the sliding plungers, a register, operating means for the register including driven elements carried by the register, driving elements connectible and disconnectible with the driven 120 elements under the control of the key operated means, and a swinging frame actuated from the key operated means and engageable with the driving elements for actuating 125 the same. 130

9. In a change making device, a money changing unit including a plurality of coin holders, ejectors for the coin holders, a plurality of sliding plungers, and means for mounting the plungers for sliding movement including rollers, keys controlling the engagement of the plungers with the ejectors and key operated means for actuating the plungers.
10. In a change making device, a money changing unit including a plurality of coin holders, ejectors for the holders, a plurality of sliding plungers, key operated means controlling the sliding plungers including a plurality of levers, a single key controlling said levers, and motion transmission means between the levers and the plungers, slide rods connected with the levers and constrained to partake of the movement of the plungers,
- locking mechanism cooperable with the slide rods, shiftable connecting elements between the sliding plungers and the ejectors, keys for selectively controlling said shiftable connecting elements and means under the control of the keys for releasing the locking means.
11. In a change making device, a money changing unit including a plurality of coin holders, ejectors for the coin holders, a plurality of sliding plungers, key operated means controlling the plungers, shiftable connecting elements between the plungers, and the ejectors, a plurality of keys, a lever actuated from each key, a lifting lever connected to each of said levers and to a shiftable connecting element.

ANGELO PAPOULIAS.
